UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

CONSTRUCTIONAL MATERIAL COMPRISING RAIL FILLER FUNCTIONING AS AN EXPANSION JOINT

Application filed December 5, 1927. Serial No. 237,833.

This application is a continuation in part of my application Serial No. 472,319, filed May 25, 1921, Patent No. 1,662,567, issued March 13, 1928, relating to constructional material wherever expansion and contraction must be provided for.

A rail filler acts as an expansion joint between the rail and adjacent paving. The previous art teaches that one of the features 10 of expansion joint is to take up expansion and contraction between the paving and the rail.

This invention relates particularly to the elevations and depressions molded in the material itself, which lock the material with the paving or lock the paving with the material, and relates to constructional material adapted for use as a rail filler to take up the expansion and contraction between paving elements and as constructional material which can be locked in the paving, yet not lock adjacent paving members or adjacent rigid members in themselves.

This invention relates particularly to a 25 flexible board-like structure in contra-distinction to a rigid, board-like structure, and is composed of vegetable fibers of various kinds, such as, flax, hemp, straw, or any other ingredients which may be suitably matted together 30 in felted form, or otherwise interwoven, as is customary in forming such fibrous material into continuous sheets. This vegetable material may be waterproofed or not, as is preferred, by injecting therein any bituminous or petroleum waterproofing saturants 35 adapted thereto, thus making the material waterproof but not destroying the felted, matted form, which gives to the expansion joint the inherent power of compression 40 within itself and the power to re-expand of its own accord. The use of such fibrous material prevents breakage of the joint, thus enabling it to be handled in a rough manner and still not be destroyed, whereas all solid bituminous joints, whether provided with felt sides or otherwise, become very brittle in cold 45 weather and a minimum shock often breaks or cracks the entire joint.

Another object of my invention is to mat 50 this fibrous material together in such a man-

ner that it may present smooth sides to the face of the concrete, and by rolling or forming this matted, fibrous material between rollers, making various formations thereon in the shape of elevations and depressions or corrugations against which the concrete is formed, such elevations and corrugations being uniform and oppositely constructed so that the thickness of the expansion joint at any one point is uniform; thus, if a corrugation is elevated on one side the opposite side of that elevation would be depressed on the opposite side of the joint. The purpose of these elevations and depressions primarily is to prevent the joint from creeping out of the crevice. 55

Another object of my invention is to form this fibrous material as in matted form in a wet condition, then run through form presses or suitable machinery to mat the material together. The material should then preferably be dried, either in warming ovens or otherwise, and if desired, suitably waterproofed. 60

With reference to the drawings which accompany and form a part of this specification: 65

Figure 1 represents a section of constructional material showing elevations D, depressions E, and irregularly overlapping, 70 foliated mats F.

Figure 2 illustrates a cross-section of Figure 1, showing depressions E, elevations D, and foliated, irregularly overlapping mats F. 75

Figure 3 illustrates a cross-section of Figure 4, showing depressions E, elevations D and foliated, overlapping mats F. 80

Figure 4 illustrates a body section of the structure shown in cross-section Figure 3, in which D represents the elevations, E the depressions and F the irregularly overlapping, 85 foliated mats.

Figure 5 illustrates the locking or molding of the paving material in the face of the constructional joint without locking the slabs, as shown along the lines H, G representing the concrete, D the elevations and E the depressions. 90

Figure 6 illustrates a rail filler functioning 95 as an expansion joint having elevations D 100

and depressions E, and a body structure composed of foliated, irregularly overlapping mats F. In this modification one face surface 5 may be smooth to completely fill the rail cavity, the exposed face only being provided with the depressions and projections to lock with the paving. The exposed face may be advantageously extended to project along the ball of the rail to separate the pavement therefrom.

My invention consists of irregularly overlapping fibrous mats of waterproofed material assembled together into a block-like structure. The linear fibrous elements may 15 exist by reason of the felting between the overlapping, fibrous mats. The fibrous material may be suitably matted together in any convenient form and waterproofed before or after felting. By felting I mean gathering together the fibrous elements and forming same into sheet form.

I claim:

1. A preformed rail filler functioning as an expansion joint, comprising a flexible, 25 boardlike strip embodying in its structure interrupted and substantially parallel mats of vegetable fibers pressed together and irregularly overlapping one another.

2. A preformed rail filler functioning as an 30 expansion joint, comprising a flexible, boardlike strip made up of interrupted and substantially parallel mats of linear fibers of various kinds, said mats irregularly overlapping one another.

3. A preformed rail filler functioning as an 35 expansion joint, comprising a waterproofed, blocklike strip embodying in its structure interrupted and substantially parallel mats of fibrous material irregularly overlapping one another.

4. A preformed rail filler functioning as an expansion joint, comprising waterproofed, interrupted and substantially parallel mats of fibrous material in varying 45 dimensions, and finely divided fibrous material, and assembled in irregular, overlapping, blocklike structure.

5. A preformed rail filler functioning as an 50 expansion joint, comprising a flexible, boardlike strip embodying in its structure interrupted and substantially parallel mats of fibrous material irregularly overlapping one another and permeated with bituminous material.

6. A preformed rail filler functioning as a 55 means to take up expansion and contraction between constructional material, composed of compressible and expandable material, provided on its opposite faces with integral, 60 relatively shallow depressions and projections for the purpose of preventing the strip from being bodily dislocated from its position between adjacent constructional sections.

7. A preformed rail filler functioning as an 65 expansion joint, comprising a mixture of bi-

tuminous material, fibrous mats and finely divided fibrous material, said mats being waterproofed, and forming a structure composed of interrupted and substantially parallel mats of fibrous material in varying dimensions and finely divided fibrous material assembled in irregularly overlapping relation.

8. A preformed rail filler functioning as an expansion joint, comprising a mixture 75 of bituminous material and fibrous mats, formed into a blocklike structure, having upon at least one of its faces elevations and depressions for the purpose of locking the face of the filler to the face of the constructional material placed against it.

9. A preformed rail filler functioning as an expansion joint, comprising a waterproofed, flexible, boardlike strip embodying in its structure interrupted and substantially parallel mats of fibrous material irregularly overlapping one another, and having upon the face which is presented to the constructional material contacting with the preformed constructional material, elevations 80 and depressions for the purpose of locking the face of the filler with the constructional material placed against it, said elevations and depressions being formed in the surface of the filler and retaining its form without 85 becoming part of the constructional material placed against it.

10. Preformed constructional material in the form of a rail filler functioning as an expansion joint, comprising fibrous material and a waterproofed binder, having elevations and depressions embossed upon a surface thereof for the purpose of engaging the surface in interlocking relation with a rigid constructional material placed in contact 100 with the elevations and depressions, said elevations and depressions remaining independent and not becoming a part of the constructional material placed against it.

11. The herein described method of locking a rigid constructional material with a flexible, non-rigid material functioning as an expansion joint, by impressing elevations and depressions in the face of the non-rigid material, permitting the rigid material when 110 plastic to be poured against the non-rigid material and contacting the inverted form, thus locking the rigid material when set with the non-rigid material and so limiting the elevations and depressions that the rigid structural elements will not in themselves interlock with each other.

12. The herein described method of locking a rigid constructional material with a flexible, non-rigid material functioning as an expansion joint, by impressing elevations and depressions in the face of the non-rigid material, permitting the rigid material when 115 plastic to be poured against the non-rigid material and contacting the inverted form, 120

130

thus locking the rigid material when set with the non-rigid material and so limiting the elevations and depressions that the rigid structural elements will not in themselves interlock with each other, the elevations and depressions remaining independent and not becoming a part of the plastic material poured against the elevations and depressions.

13. The herein described method of locking rigid constructional material with a flexible, non-rigid material functioning as an expansion joint, by impressing elevations and depressions in the face of the non-rigid material, permitting the rigid material when plastic to be poured against the non-rigid material, said material taking the form of the face of the non-rigid material, thus enabling the rigid material to lock with the face of the non-rigid material without said non-rigid material becoming a part of the rigid material.

14. In a preformed construction material comprising a flexible, boardlike strip embodying in its structure separate mats of fibers and a bituminous material bonding said mats together.

Signed at Chicago, Illinois, this 2nd day of December 1927.

ALBERT C. FISCHER.
